(57) **CLAIM**

The ornamental design for an electric hair straightener as shown and described.

DESCRIPTION

FIG. 1 is a top, front and right side perspective view of an electric hair straightener showing my new design;
FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is an enlarged top plan view thereof;

FIG. 8 is an enlarged bottom plan view thereof; and,

FIG. 9 is a top, front and right side perspective view showing the electric hair straightener in another configuration.

The broken lines in the drawings illustrate portions of the electric hair straightener, which form no part of the claimed design. The additional broken lines in FIG. 9 are to show environment and form no part of the claimed design.
